ATTACHMENT FOR ELECTRIC RAZORS

John E. Gantner, Utica, N. Y.

Application July 10, 1942, Serial No. 450,446

6 Claims. (Cl. 30--90)

My invention relates to a rocking motion for electric razor and I declare the following to be a full, clear, concise and exact description thereof sufficient to enable anyone skilled in the art to which it appertains to make and use the same, reference being had to the accompanying drawings in which like reference characters refer to like parts throughout the specification.

The object of the invention is to provide a device for rocking an electric razor when in use, whereby to aid in increasing its effectiveness in severing the beard from a person's face. Heretofore, in the use of an electric razor, it has been necessary to rock the razor with the hand in order to get a clean shave. The present invention is designed to simulate the movements of the hand to accomplish the desired results. To this end an outer casing having bearing members to be attached to the ordinary electric razor is used. There are means within the outer casing for rocking the electric razor casing, an electric motor for actuating said means. The device can be applied to the ordinary electric razor.

The object will be understood by referring to the drawings in which:

Fig. 1 is a perspective view of the device.

Fig. 2 is an elevational view showing the central vertical section of the attachment.

Fig. 3 shows a detail view of an end view of 30 an electric razor broken away and parts of actuation mechanism applied thereto.

Fig. 4 shows a central vertical section of a modified form of the attachment.

Fig. 5 is a detail enlarged view of a cam and 35 strap employed.

Fig. 6 shows a modified form of the electric razor, with the attachment applied thereto.

Fig. 7 shows a central vertical section of Fig. 5, parts being in full.

Fig. 8 shows a detailed enlarged view showing a perspective of a modified form of the device, parts being broken away.

Fig. 9 is a diagrammatic view of the wiring.

Referring more particularly to the drawings, the device embodies a casing 1 within which is supported on trunnions 2, 2 any ordinary electric razor 3 similar to the Schick or Remington type. Casing 1 is open at its front and rear ends. It encloses the larger portion of the razor 3 leaving the front part 4 containing the shearing mechanism exposed for use in shaving the beard of a person. Furthermore, casing 1 is spaced from the outer casing 5 of razor 3, whereby to allow for a limited amount of rocking motion of elec-

tric razor 3. Trunnions 2, 2 are fastened to opposite lateral walls 6, 6 of casing 1 being projected through suitable apertures therein and anchored in bosses 10, 10 that are welded or otherwise secured to the inner opposite surfaces of walls 6, 6.

Furthermore, trunnions 2, 2 project inward and rest in loose bearings 11, 11 made in the casing 5 of razor 3. Bearings 11 may be made 10 any suitable distance from the ends of razor 3, whereby to allow for a predetermined amount of rocking thereof.

A shelf 15 is made integral with the lower part 16 of casing 5. It projects rearwardly from 15 said casing 5 and is engaged by a disk 17 eccentrically mounted on power shaft 20 of electric motor 21 which is supported by the base 7 of casing 5.

Disk 17 turns with shaft 20, whereby to cause 20 electric razor 3 to rock on its trunnions 2, 2. Said disk 17 engages shelf 15 for this purpose. The means for rocking razor 3 in the opposite direction to return razor 3 to its normal position 25 contemplates a coiled spring 22 that is fastened at one end to an outer corner 23 of shelf 15 and at its opposite end to the underside of the top of casing 1.

Wires 25, 25 are in electric circuit with the motor, not shown that actuates the shearing knives 26 and 27 are connected to motor 21, whereby to energize said motor 21.

The terminals for the electric circuit that energizes the motor not shown which actuates the shearing knives 26 and 27 and the motor 21 are shown at 30, 30.

In operation, the user will connect the plug switch to the house circuit, now shown, with terminals 30, 30 which will actuate shearing knives 26 and 27 and also eccentrically mounted disk 17. He then grasps casing 1 and using it 40 as a handle will move razor 3 over the parts of his face to effect a clean shave. As the razor 3 is moved over his face the razor 3 will rock on its pivots or trunnions 2, 2 to effect the motion heretofore made by his hand alone. At the same time the shearing knives 26 and 27 will sever his beard.

The modification shown in Fig. 4 embodies 50 strap rings 35, 35 fastened to the bottom surface of electric razor 3 in which turns cams 36, 36 mounted eccentrically on shaft 37, which is supported in a bearing in journal block 38 secured to the outer casing 40 and also in a bearing in support 41 secured to casing 40. A pinion 42 is 55 fixed to revolve with shaft 37 and is in mesh with

spur gear 43 mounted to turn with power shaft 44 of electric motor 45. Motor 45 is supported on member 41. The ratio of gear 43 to the pinion 42 will cause shaft 31 to revolve much faster than shaft 44.

Laterally extending pins 50, 50 extend from opposite sides of electric razor 3. Pins 50, 50 engage guide slots 51, 51 made in the inner side walls of casing 40.

The front end of casing 40 is open as in the former structure, whereby to expose the front end 52 of the electric razor 3.

The electric terminals 55, 55 of the motor not shown of razor 3 are connected in electric circuit with the terminals of motor 45, whereby to cause both motors to operate simultaneously.

In operation, the user will plug in terminals 55, 55 with the house circuit, whereby to actuate the knives of the razor and to cause the rotation of power shaft 44 and through gear 43 and pinion 42, and shaft 31 whereby cams 36, 36 will move razor 3 up and down to simulate the said motion usually applied by the user of the razor 3. Casing 40 will be used as a handle for moving the blades over the face.

The modification shown in Figs. 6 and 7 embodies an electric razor having cylinder shearing knives 60 and 61. Shearing knife 60 is in the form of a cylinder, as above indicated. It has a relatively thick end wall 67 and is mounted to turn with power shaft 65. To this end a set screw 63 is projected through the reduced rearwardly extended part 64 to engage shaft 65. The opposite end of cylinder knife 60 is open. Its lateral outer surface is formed with teeth 66 made by cutting alternate slots 68 through said surface. Solid parts 69 are left at diametrically opposite locations.

The co-operating cylinder knife 61 is fitted to slide axially within knife 60. Its outer surface is in contact with the inner surface of knife 60. Teeth 70 are made in the outer surface of knife 61 by cutting alternate slots through its surface, whereby the axial movement of knife 61 relative to the stationary knife 60 will effect a shearing action to cut the beard of the person using the same. An annular slot 72 is made in the body of knife 61 to aid in the formation of teeth 70. Solid parts are left between teeth 70 at diametrically opposite locations similar to parts 69 of knife 60.

The means for moving cylinder knife 61 reciprocally and axially relative knife 60 contemplates a pin 75 projected through the reduced rearwardly extended sleeve part of knife 61. Said pin 75 projects into an endless spiral guide groove 77 made in power shaft 65, whereby the turning of shaft 65 will cause pin 75 to travel in said spiral groove 77 and thereby reciprocate cylindrical knife 61 relative to knife 60, to cause the teeth 70 of said cylinder 61 to effect a shearing action with co-operating teeth 66 or cylinder 60 to cut the person's beard.

Knife 61 is splined to shaft 65 by providing a key 80 that fits into an open elongated co-operating aligned recess 81 made in shaft 62 adjacent its end and in the body 83 of cylinder knife 61. Said recesses 81 are no longer than key 55, whereby to permit of the axial movement of knife 61 relative knife 60 as above mentioned.

Shaft 62 extends to the rear and is enclosed by a hollow cylindrical casing 84 that supports said shaft in bearing 85 at the front end thereof.

Shaft 65 projects through the center of an electric motor 86, having plug in electric terminals

87, 87 that extend into the indenture or open recess 88 formed in the rear end of casing 84.

Motor 86 may be fastened to the inner surface of cylindrical casing 84 at 89, 89.

5 In operation, the user will plug in on terminals 87, 87 to some house circuit and then by taking hold of cylinder casing 84 and using it as a handle move the shearing blades 60 and 61 over his face to effect a clean shave. As said blades 60 and 61 move over the face, both blades will revolve with shaft 65 because of the splined connection of cylinder 61 with shaft 65 and of the set screw connection of cylinder 60 at 63. Furthermore, blade 61 will be reciprocated axially 15 with respect to blade 60 which is stationary in an axial manner because of the pin 75 travelling in spiral guide groove 77 in shaft 65, whereby to cause the teeth 70 of cylinder blade 61 to co-operate with the teeth 66 of cylindrical blade 60.

20 In place of spring 22 shown in Figs. 2 and 3 a metal strap such as 35 shown in Fig. 5 could be used to rock the electric razor 3 on its pivots 11, 11.

The modification is shown in Fig. 8 where the 25 strap 35 is welded or otherwise secured to shelf 15.

Fig. 9 shows a diagrammatic plan of the wiring of the two electric motors, that is motor 90 for actuating the shearing knives 26 and 27 and the 30 other 21 for rocking electric razor 3. Motor 21 for controlling the actuation of knives 26 and 27 has one terminal 30 connected to wire 25 leading to wire 97 of the 110 volt house circuit and its opposite terminal 30 to the other wire 25 leading to the opposite wire 100 of the 110 volt house 35 circuit.

Likewise, motor 90 controlling the rocking motion, has one terminal 102 connected to said wire 25 leading to the wire 97 and the opposite terminal 103 connecting to the other wire 25 leading to said wire 100.

Having thus described my invention what I claim as new and desire to secure by Letters Patent is as follows:

45 1. In an attachment for electric razors, a casing for enclosing a razor, pivotal means in said casing for mounting said razor, a shaft mounted for rotation in said casing, a disk eccentrically mounted on said shaft and engaging said razor 50 for rocking said razor in one direction and means for rocking said razor in the opposite direction.

2. In an attachment for electric razors, a casing having means for pivotally mounting said razor, a shaft mounted for rotation, and an eccentrically mounted disk on said shaft and engaging said razor to aid in rocking the same, whereby to aid in shaving.

3. In an attachment for electric razors, a casing enclosing said razor, pivots for mounting said 60 razor to said casing, a shelf formed on said razor at some distance from the line joining said pivots, a disk engaging said shelf and mounted eccentrically to a shaft carried in said casing, an electric motor mounted in said casing for rotating said shaft, whereby to rotate said disk to effect a rocking of said razor to aid in shaving, and a spring connected to said razor and to said casing to urge said shelf against said disk.

65 4. In an attachment for electric razors, a casing enclosing a razor, pivots supported by said casing for mounting said razor to said casing, a shelf formed on said razor at a distance from the line through said pivots, a shaft mounted in bearings in said casing, an eccentrically mounted disk on said shaft engaging said shelf, whereby

70 75

to rock said razor in one direction and spring means attached to said razor for rocking said razor in the opposite direction.

5. In an attachment for electric razors, a casing, means for pivotally mounting said razor, a circular strap secured to said razor, a shaft mounted to rotate in said casing, a disk eccentrically mounted on said shaft and engaging said strap, whereby to rock said razor.

6. In an attachment for electric razors, a casing, means for pivotally mounting said razor, a shelf formed on said razor, a circular strap secured to said shelf, a disk mounted in said strap, a shaft eccentrically secured to said disk, and means to rotatably mount said shaft, whereby when said shaft is rotated the razor will be rocked.

JOHN E. GANTNER.
